APPARATUS FOR CHARGING STORAGE
BATTERIESNorman F. Agnew, Wilkinsburg, Pa., assignor to
The Union Switch & Signal Company, Swiss-
vale, Pa., a corporation of Pennsylvania

Application January 14, 1936, Serial No. 59,035

6 Claims. (Cl. 171—314)

My invention relates to apparatus for charging storage batteries.

One object of my invention is the provision of novel and improved means for automatically decreasing the rate of charge of a storage battery when the battery becomes substantially fully charged.

I will describe two forms of apparatus embodying my invention, and will then point out the novel features thereof in claims.

In the accompanying drawing, Fig. 1 is a view partly in elevation, partly in section, and partly diagrammatic illustrating one form of apparatus embodying my invention. Fig. 2 is a view similar to Fig. 1 showing a modification of the apparatus illustrated in Fig. 1.

Similar reference characters refer to similar parts in both views.

Referring first to Fig. 1, the reference character T designates a transformer, the primary 4 of which is constantly connected with the terminals X and Y of a suitable source of current not shown in the drawing, and the secondary 2 of which is constantly connected with the input terminals 3 and 4 of a full wave rectifier R. The output terminals 5 and 6 of rectifier R are connected with the terminals of a storage battery B of the usual type in series with a resistance 7. The value of the resistance 7 is such that when this resistance is included in the charging circuit, the battery will be charged at a relatively low rate, but that, if this resistance is short circuited, the battery will then be charged at a relatively rapid rate.

Associated with the battery B is a switch S embodying my invention for at times short circuiting the resistance 7. This switch is adapted to be operated by gas pressure caused by the gassing of the battery when the battery becomes approximately fully charged as will be explained more fully hereinafter, and in the form here shown, this switch comprises a casing 8 consisting of a hollow lower part 8^a which is adapted to be screwed into one of the usual filler cap openings 9 in the battery B, and a hollow upper part 8^b which is bolted to the lower part 8^a by means of bolts 10. Clamped between the lower and upper parts 8^a and 8^b of the casing 8 is a flexible diaphragm 11 of suitable material, such for example as rubber, which diaphragm divides the inside of the casing into an upper compartment 8^c and a lower compartment 8^d. Disposed within the upper compartment 8^c is a lever 12, one end of which is pivotally attached at point 12^a to the part 8^b of the casing 8, and the other end of

which carries a spherical part 13 which rests on the upper side of the diaphragm 11 in such manner that vertical movement of the diaphragm 11 will cause rotation of the lever 12 between a lower extreme position in which it is shown in the drawing and an upper extreme position. A mercury contact 14 of the usual and well-known construction is secured to the lever 12 by means of a clamp 12^b in such manner that this contact will be closed or open according as the lever 12 occupies its lower or upper extreme position, and the terminals of this contact are secured by means of flexible connectors 15 and 16 with terminal posts 17 and 18 which are mounted in the top of the part 8^b of the casing 8. The terminal posts 17 and 18, in turn, are connected with the opposite ends of the resistance 7, and it will be seen, therefore, that the resistance 7 will be short circuited by the contact 14 when the lever 12 occupies its lower position in which it is shown in the drawing, but not when this lever occupies its upper position.

The lower part 8^a of the casing 8 is provided with two vents 21 and 22 which connect the compartment 8^d with the outer atmosphere. The vent 21 is normally closed by a gravity operated safety release valve 23, and is of such size that when this vent is open, any gases which are generated in the battery B due to the charging current at any state of charge of the battery can escape through this vent sufficiently rapidly to prevent any appreciable pressure from building up in the compartment 8^d. The valve 23 is so constructed that it will open when and only when the gas pressure in the compartment 8^d exceeds that required to move the diaphragm 11 upwardly to the position in which the contact 14 is opened. The vent 22 is of such size that any gases which are generated in the battery B due to the charging current when the state of charge of the battery is below that at which the battery begins to gas rapidly will be permitted to escape through this vent at a rate which will prevent any appreciable pressure from building up in the compartment 8^d, but that, the gases which are generated due to the charging current when the battery becomes charged to the potential at which it begins to gas rapidly will cause sufficient pressure to be built up in the compartment 8^d to force the diaphragm 11 upwardly to the position in which the contact 14 opens.

The operation of the apparatus shown in Fig. 1 as a whole is as follows: A cell on charge will begin to gas at about two and three tenths volts. The point of gassing depends upon the voltage.

but the amount of gassing depends upon the current. At high rates of charge, the battery will be about 80 per cent fully charged when it starts to gas rapidly, but at lower rates of charge the percentage of charge at which the battery begins to gas rapidly will be higher. It will be seen, therefore, that when the battery B is discharged below the state of charge at which it begins to gas rapidly, the battery, if 10 it gasses at all, will gas at too slow a rate to cause sufficient pressure to build up in the compartment 8^d to open the contact 14, and as long as this contact remains closed, the resistance 7 will be short circuited, thus causing the battery 15 to be charged at the high rate. As soon, however, as the battery becomes charged to the state of charge where it begins to gas rapidly, the pressure in the compartment 8^d will then build up to a value which is sufficient to force the 20 diaphragm 11 upwardly and open the contact 14. The opening of this contact will remove the short circuit from the resistance 7, and as a result, the charging current will then become automatically decreased to the low rate. A slight 25 amount of gassing will hold the diaphragm 11 in its upper position after it has once been moved to this position, and the parts are so proportioned that the amount of gassing which takes place due to the low rate of charge will be sufficient 30 to hold this diaphragm in its upper position as long as the battery remains approximately fully charged. If, however, the cell becomes discharged to the point where the battery quits 35 gassing rapidly, enough gas will escape from the vent 22 to allow the diaphragm to move downwardly to the position in which contact 14 becomes closed. The closing of contact 14 will, 40 of course, cause the battery to again become charged at the high rate. It will be seen, therefore, that with apparatus embodying my invention, it is possible, by properly proportioning the parts, to maintain the battery at its approximately fully charged value regardless of the 45 manner in which the load on the battery varies without danger of damage to the battery.

Referring now to Fig. 2, in the modified form of the apparatus here illustrated, I employ a switch S¹ which is of somewhat different design from the switch S shown in Fig. 1. As here 50 shown, the switch S¹ includes a relay C comprising a winding 25 mounted on an inverted U-shaped magnetizable core 26 which is secured to the part 8^b of the casing 8 within the compartment 8^c. The relay C also comprises an armature 27 which is attached to one leg of the core 26 for swinging movement toward and away from the other leg of the core. One terminal of winding 25 of relay C is connected 55 with a terminal post 28 which is mounted in the side wall of the part 8^b of the casing, and the other terminal of this relay is connected with the terminal post 18. The terminal post 28, in turn, is connected with the positive terminal 60 of the battery B through a switch 29, and it will be seen, therefore, that when the switch 29 is closed, the winding 25 will be constantly supplied with current from the battery B, but that, when the switch 29 is open, the supply of 65 current to the winding 25 will be interrupted. The resistance of the winding 25 is such, and the parts are so proportioned, that the current which flows in this winding will not be sufficient 70 to pick up the armature 27, but will be sufficient to hold the armature in its picked up position 75

once it is moved there. It follows, therefore, that when the armature is once picked up it will remain picked up until the switch 29 is opened to deenergize the winding 25.

The armature 27 carries a contact member 5 38 which is secured to, but insulated from, the armature, and this contact member cooperates with a fixed contact member 31 secured to, but insulated from, the core 26, to form a contact 10 38-31 which is closed or open according as the 15 armature occupies its released position in which it is shown in the drawing, or its attracted position. The contact 38-31 is adapted to take the place of the mercury contact 14 shown in Fig. 1, and to this end the contact member 38 20 is electrically connected by means of the flexible connector 16 with the terminal post 18, while the contact member 31 is electrically connected by means of a connector 18 with the terminal post 17. It will be seen, therefore, 25 that the resistance 7 will be short circuited by the contact 38-31 when the armature 27 is released, but not when this armature is picked up. The armature 27 also carries a depending arm 27^a which cooperates with the upper end of an operating rod 32 which is secured to the diaphragm 11, the parts being so proportioned that upward movement of the diaphragm 11 due to 30 gas pressure in the compartment 8^d will move the armature from its released position to its attracted position. The lower end of the operating rod 32 is operatively connected with a safety release valve 33 which controls the escape of gas from the compartment 8^d to atmosphere through the vent 21. The parts are so proportioned that the valve 33 will normally be held closed by gravity, but that, when the diaphragm 11 is moved upwardly to the position in which the armature 27 occupies its attracted position, the operating rod 32 will open this valve. 35

The operation of the apparatus shown in Fig. 2 is as follows: When the relay B is discharged below the point where the battery starts to gas, the parts normally occupy the positions in which they are shown in the drawing, and under these 45 conditions, the resistance 7 is short circuited by the contact 38-31 so that the battery B is charged at the high rate. As soon, however, as the battery becomes charged to the point where it starts to gas, the pressure in the compartment 8^d will 50 build up, and when this pressure has increased to a predetermined value, the diaphragm 11 will move upwardly, and will thus move the armature from its released to its attracted position, and the release valve 33 from its closed to its open 55 position. The upward movement of the armature 27 will open the contact 38-31, and will thus cause the battery to become charged at the low rate, while the opening of the release valve 33 will permit gas to escape from the compartment 8^d to atmosphere until the pressure in the compartment 8^d decreases to some value at which the valve will close just far enough to permit the gas in the compartment 8^d to escape at a relatively slow rate. As was previously pointed out, 60 when the armature 27 is once picked up, the current flowing in the winding 25 will cause the armature to remain picked up as long as the switch 29 remains closed, and it follows, therefore, that the battery will subsequently continue 65 to be charged at the low rate until the switch 29 is opened. As illustrated in the drawing, the switch is manually operated, but it should be particularly pointed out that this switch may be 70 operated in any desired manner. 75

One advantage of apparatus embodying my invention is that it insures that the battery will be maintained at a state of maximum charge at all temperatures.

5. Another advantage of apparatus embodying my invention is that a large amount of power is available for operating the pressure operated switch, and this power is independent of temperature, vibration, relay iron variations, small 10 marginal differentials, etc.

Although I have herein shown and described only two forms of apparatus embodying my invention, it is understood that various changes and modifications may be made therein within 15 the scope of the appended claims without departing from the spirit and scope of my invention.

Having thus described my invention, what I claim is:

20 1. In combination, a storage battery, a resistance, charging means for said battery connected with said battery in series with said resistance, a first contact, a switch comprising a two part hollow compartment the lower part of 25 which is adapted to be screwed into one of the filler cap openings of said battery, a flexible diaphragm clamped between the two parts of said casing and dividing said casing into an upper and a lower compartment; a relay mounted in said 30 upper compartment, said relay being provided with a winding which is connected with said battery in series with said first contact, with an armature which is movable between an attracted and a released position, and with a contact which 35 is open or closed according as said armature occupies its attracted or released position, the parts being so proportioned that the current which flows in said winding when said first contact is closed will be insufficient to move said 40 armature from its released to its attracted position but will be sufficient to retain said armature in its attracted position after it is moved there; means for operatively connecting said armature with said diaphragm in such manner that said 45 armature will be moved from its released to its attracted position in response to movement of said diaphragm from a lower to an upper position, a vent for venting the lower compartment of said casing to atmosphere, a relief valve for 50 closing said vent biased to a closed position, means for operatively connecting said release valve with said diaphragm in such manner that movement of said diaphragm to its upper position will move said release valve to its open position, 55 and means for connecting said relay contact in multiple with said resistance.

2. In combination, a storage battery, a resistance, charging means for said battery connected with said battery in series with said resistance, a first contact, a switch comprising a two part hollow compartment the lower part of which is adapted to be screwed into one of the filler cap openings of said battery, a flexible diaphragm clamped between the two parts of said 60 casing and dividing said casing into an upper and a lower compartment, a relay having its winding connected with said battery in series with said first contact, a second contact controlled 65 jointly by said relay and said diaphragm, means 70 for connecting said second contact in multiple with said resistance, and means for venting said lower compartment to atmosphere when and only when said diaphragm is moved to the position in which said second contact is open.

75 3. In combination, a storage battery, a resist-

ance, charging means for said battery connected with said battery in series with said resistance, a switch comprising a two part hollow compartment the lower part of which is adapted to be screwed into one of the filler cap openings of said 5 battery, a flexible diaphragm clamped between the two parts of said casing and dividing said casing into an upper and a lower compartment, a relay having its winding at times supplied with current from said battery, a normally closed contact controlled jointly by said diaphragm and said relay in such manner that said contact will become opened if and only if said diaphragm is moved from a lower to an upper position but that when said contact once becomes opened it will 10 subsequently be held open by said relay, means for connecting said contact in multiple with said resistance, and means controlled by said diaphragm for controlling the gas pressure in said lower compartment.

20 4. In combination, a storage battery, a resistance, charging means for said battery connected with said battery in series with said resistance, a switch comprising a two part hollow compartment the lower part of which is adapted to be screwed into one of the filler cap openings of said 25 battery, a flexible diaphragm clamped between the two parts of said casing and dividing said casing into an upper and a lower compartment, a relay having its winding at times supplied with current from said battery, a normally closed contact controlled jointly by said diaphragm and said relay in such manner that said contact will become opened if and only if said diaphragm is moved from a lower to an upper position but that when said contact once becomes opened it will 30 subsequently be held open by said relay, means for connecting said contact in multiple with said resistance, and means for venting said lower compartment to atmosphere when and only when 35 said diaphragm is moved to the position in which said contact is open.

5. In combination, a storage battery, a switch, a relay provided with a winding which is connected with the terminals of said battery over 45 said switch and with an armature which controls a contact in such manner that said contact will be closed or open according as said armature is released or picked up, the parts being so proportioned that the current supplied to said winding will be insufficient to pick up said armature but will be sufficient to hold said armature picked up once it is moved to its picked up position, charging means for said battery controlled by 50 said contact, and means controlled by the gassing rate of said battery for at times moving said armature to its picked up position.

6. In combination, a storage battery, a switch, a relay provided with a winding which is connected with the terminals of said battery over 60 said switch and with an armature which controls a contact in such manner that said contact will be closed or open according as said armature is released or picked up, the parts being so proportioned that the current supplied to said winding will be insufficient to pick up said armature but will be sufficient to hold said armature picked up once it is moved to its picked up position, means for charging said battery at a relatively low or a 65 relatively high rate according as said contact is open or closed, and means for mechanically moving said armature to its picked up position when said battery begins to gas at a relatively rapid rate.
